[57] CLAIM

The ornamental design for a container for watches, jewelry, glasses, and pen, as shown.

DESCRIPTION

FIG. 1 is a perspective view showing my new design;

FIG. 2 is a front view thereof;

FIG. 3 is a left end view thereof;

FIG. 4 is a right end view thereof;

FIG. 5 is a top view thereof;

FIG. 6 is a bottom view thereof;

FIG. 7 is a rear view thereof;

FIG. 8 is a perspective view thereof, illustrating the container for watches, jewelry, glasses and pen of my design in open condition;

FIG. 9 is a perspective view of a second embodiment thereof, wherein this embodiment differs from the first embodiment by elongating the length for glasses and pen; and,

FIG. 10 is a perspective view of FIG. 9, illustrating the container for watches, jewelry, glasses, and pen of my design in open condition.
